CLAIM

The ornamental design for a computer mouse, as shown and described.

DESCRIPTION

FIG. 1 is a top plan view of a computer mouse showing my new design;

FIG. 2 is a front elevational view thereof;

FIG. 3 is a side elevational view thereof, the opposite side being identical in appearance;

FIG. 4 is a rear elevational view thereof;

FIG. 5 is a bottom plan view thereof; and,

FIGS. 6-20 are respectively top plan front side and rear elevational view and bottom plan view of a second, third and fourth embodiment of the design.

The undisclosed opposite side elevational view of the second, third and fourth embodiments is identical in appearance to the side shown.
